UNITED STATES PATENT OFFICE.

JOHN E. FITZGIBBON, OF MILWAUKEE, WISCONSIN, ASSIGNOR TO PHOENIX HOSIERY COMPANY, OF MILWAUKEE, WISCONSIN, A CORPORATION OF WISCONSIN.

DESIGN FOR HOSIERY.

Application filed November 11, 1922. Serial No. 4,264. Term of patent 7 years.

To all whom it may concern:

Be it known that I, JOHN E. FITZGIBBON, in use, showing my new design. a citizen of the United States, residing at Milwaukee, in the county of Milwaukee and State of Wisconsin, have invented a new, original, and ornamental Design for Hosiery, of which the following is a specification, reference being had to the accompanying drawing, forming part thereof.

The figure is a view of part of a stocking in use, showing my new design.

I claim:

The ornamental design for hosiery, as shown.

In witness whereof, I hereunto subscribe my name this 1st day of November, 1922.

JOHN E. FITZGIBBON.
